Attorney

UNITED STATES PATENT OFFICE.

ELMER E. CRUM, OF ELTON, PENNSYLVANIA.

RAILROAD TIE.

Application filed April 8, 1922. Serial No. 550,847.

To all whom it may concern:

Be it known that I, ELMER E. CRUM, a citizen of the United States, residing at Elton, in the county of Cambria and State 5 of Pennsylvania, have invented certain new and useful Improvements in Railroad Ties, of which the following is a specification, reference being had to the accompanying drawings.

10 This invention relates to railroad ties and has for its object to provide a railroad tie or rail support which prevents spreading of the rails and at the same time serves to hold the rail in engagement with the tie.

15 Another object of the invention is to provide a rail support wherein the outer clamps of the device serve as track gauges for the road.

It is a still further object of the invention 20 to provide a support of this character in the form of an attachment for wooden ties, wherein the outermost clamps are formed integral with the plate, and the innermost clamps detachable with means for securing 25 the innermost clamps and the plates to the tie.

With these and other objects in view, the 30 invention consists in the improved construction and arrangement of parts to be herein- 35 after more particularly described, fully claimed and illustrated in the accompanying drawings, in which:—

Figure 1 is a side elevation of railway rail supporting means, constructed in accordance with an embodiment of the invention, the conventional form of tie being shown in dotted lines, and the rails in section;

Figure 2 is a top plan view of the device, 40 with one of the clamps removed, showing the position of the sockets and openings for the fastening means;

Figure 3 is a perspective view of one of the detachable clamps.

45 Referring to the drawings, 5 designates a supporting member or plate made of metal and adapted to extend longitudinally of the conventional form of railroad tie A, the plate 5 coinciding with the tie so that the upper surface of the tie is protected. Each 50 end portion of the plate 5 is exactly the same as the other, so that the description of one will suffice for both.

Each end portion of the plate 5 is provided with a laterally extending rail groove

or seat 6, said groove corresponding in length to the width of the rail. Projecting from the upper face of each end of the tie is a rail clamping jaw 7, said jaw being formed integral with the plate, so as to prevent 60 spreading of the rails, due to side thrust of the train. The lower face 8 of the jaw 7 projects over the groove 6 and is constructed to conform to the contour of the base of the rail, the lower portion 9 of the face 8 65 merging with the ends of the grooves 6 so that the jaw 7 cooperates with the groove to provide a recess corresponding to the shape of the lower portion of a rail in cross section.

70 Each of the stationary jaws 7 extends inwardly of the plate, so that it is impossible for either one of the rails to spread. In order to permit the rails to be readily inserted in the groove, and beneath the jaws 7, a 75 movable or detachable clamp 10 is provided, said clamp having its upper surface 11 rounded, similar to the upper surface of the jaw 7, while the outer end thereof is inwardly beveled as at 12, the inwardly beveled portion cooperating with the inner end wall of the groove 6 to conform to the shape of the base of the rail, similar to the jaw 7, and outer end wall of the recess. The plate 5 is provided, adjacent the inner wall of 80 the groove 6, with a pair of spaced sockets 13, while depending from the detachable clamp 10 adjacent the beveled end 12 are a pair of spaced pins 14 adapted to enter the sockets 13 so as to prevent lateral movement 85 of the detachable clamp 10 and to also assist in holding the clamp in engagement with the rail.

90 The plate 5 is provided with an opening or bore of the tie 17 adjacent the inner wall 95 of each of the grooves 6, and between the sockets 13. The bore 16 is intended to register with a bore 17 provided in the tie A, the lower portion of the bore 17 being enlarged to receive the head of a bolt 18, so as 100 to prevent movement of the bolt and at the same time permit the tie to rest evenly on the road bed. The opposite end of the bolt, or that end which extends through the opening 16 of the clamp 10, is 105 intended to receive a nut to not only clamp the clamp 10 to the plate 5, but to clamp the plate 5 to the tie. In addition to preventing lateral movement of the clamp 10, the pins 14 also serve to a large extent to relieve the 110

main securing bolt 18 of a greater portion of the strain, longitudinal movement of the clamp 10 being also prevented.

From the foregoing it will be readily seen that this invention provides a novel form of railroad tie wherein the rails are not only prevented from side movement through the side thrust of the train, but wherein the device may be used as a gauge for the rails. In this way the tracks will always be maintained in the proper gauge. In addition to this, the inner clamps of the device are removed so that it is possible to readily insert the rail in the groove of the device and in engagement with the stationary jaws thereof. Another important feature of this tie is that it is composed of only two parts, namely, the supporting plate and the movable clamps, spikes being eliminated, as the bolts 18 are sufficient to hold not only the plate in engagement with the tie, but the movable clamps in engagement with the plate. Another important feature of this device is that the plate 5 is provided with a plurality of openings 19 for the reception of

spikes to spike the same to a tie when it is desired to use the same as a track gauge.

What is claimed is:—

An attachment for railway ties comprising a tie plate adapted to engage the upper surface of the tie, said plate coinciding with the tie, stationary clamps formed on the upper face of the plate inwardly of the ends of the plate, said plate having rail grooves, the grooves extending beneath the stationary clamps, and detachable clamps disposed inwardly of the stationary clamps, each of the detachable clamps consisting of a block having one edge thereof undercut to provide a shoulder and a rail engaging jaw, pins depending from the lower surface of the block adjacent the jaw, said pins being adapted to enter sockets provided in the plate to position the shoulder of the block substantially flush with the inner wall of the rail groove, and fastening means extending through each detachable clamp, the tie plate and the tie.

In testimony whereof I hereunto affix my signature.

ELMER E. CRUM.
